CLAIM

I claim the ornamental design for an electronic device, as shown and described.

DESCRIPTION

FIG. 1 is a front perspective view of an electronic device in accordance with the present design;

FIG. 2 is a rear perspective view of the electronic device in FIG. 1;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is an enlarged view of the encircled portion of the electronic device shown in FIG. 2; and,

FIG. 10 is an enlarged view of the encircled portion of the electronic device shown in FIG. 5.

The broken lines in the figures show portions of the electronic device that form no part of the claimed design.

1 Claim, 5 Drawing Sheets
